UNITED STATES PATENT OFFICE.

FRANK SOHN, OF CHICAGO, AND LOUIS G. MARMION, OF VILLA PARK, ILLINOIS, ASSIGNORS TO THE VITROLITE COMPANY, A CORPORATION OF WEST VIRGINIA.

DESIGN FOR A COUNTER.

Application filed August 17, 1927. Serial No. 23,128. Term of patent 7 years.

To all whom it may concern:

Be it known that we, FRANK SOHN and LOUIS G. MARMION, respectively, citizens of the United States and of the French Republic, respectively, residing at Chicago and Villa Park, in the county of Cook and State of Illinois, have invented a new, original, and ornamental Design for Counter, of which the following is a specification, reference being had to the accompanying drawing, forming part thereof.

The figure is a perspective view of a counter, showing our new design.

We claim:

The ornamental design for a counter, as shown.

FRANK SOHN.
L. G. MARMION.
